UNITED STATES PATENT OFFICE

2,099,270

APPARATUS FOR COATING WIRE

Owen A. McNamee, Worcester, Mass.

Application November 25, 1936, Serial No. 112,832

2 Claims. (Cl. 117—40)

This invention relates to an apparatus for coating wire.

In the manufacture of electrical wiring which is intended for subjection to high temperatures, considerable difficulty has been experienced in providing a proper protective coating. Taking locomotive headlight wire as an example, the high temperature of the boiler necessitates an effective heat-resistant coating, such as asbestos. It is, therefore, highly desirable to provide an electrical conductor wire which is first coated with asbestos fibers and then saturated with a waterproof material, such as asphalt, after which it may be encased in a braid or other suitable covering.

It is, accordingly, among the objects of the present invention to provide an apparatus for coating wire which may be efficiently employed to rapidly deposit an effective heat-resistant fiber coating on electrical wiring; after which it may be treated in any manner well known in the art.

The foregoing and other objects will become apparent after referring to the drawings, in which:

Figure 1 is a plan of a preferred form of apparatus;

Figure 2 is a sectional view on the line II—II of Figure 1;

Figure 3 is a sectional view on the line III—III of Figure 1.

Figure 4 is a sectional view on the line IV—IV of Figure 1.

Figure 5 is a sectional view on the line V—V of Figure 1.

Figure 6 is a sectional view on the line VI—VI of Figure 1.

Figures 7 and 8 are fragmentary sectional views of details.

The numeral 2 designates a frame which carries a rotatable spindle 3 having a central longitudinal aperture 4. This rotatable spindle 3 carries a circular plate 5 which has a central aperture 6 in alignment with the aperture 4 of the former. A gear 7 is secured to the rotatable spindle 3 and is driven by an adjacently disposed gear 8 which derives its rotation from any suitable source. In this manner both the spindle 3 and circular plate 5 are rotated.

The circular plate 5 carries a rotatable shaft 10 which extends from both sides thereof and has a gear 12 secured to its end adjacent the frame 2. This gear 12 meshes with a stationary gear 13 which is secured to the frame 2. The end of the rotatable shaft 10 which extends from the

other side of the circular plate 5 has a gear 15 secured thereto.

The circular plate 5 carries on its side adjacent the frame 2 shafts, as shown at 17, 18, 19, and 20, which are geared together by their respective gears 21, 22, 23, 24, the last three being considerably smaller than the gear 21 on the shaft 17. This gear 21, besides meshing with the gear 22 on the shaft 18, also meshes with the gear 15 on the shaft 10. The gears 22 and 23 are merely idler gears serving to rotate the gear 24 and shaft 20, as will be explained.

The rotatable shafts 17 and 20 carry contacting carding rolls 25 and 26, respectively. These contacting carding rolls 25 and 26 are, of course, provided with the usual card teeth.

A series of rotatable shafts 30, 31, and 32 are mounted on the side of the circular plate 5, which is opposite the frame 2, in the manner of the previously mentioned rotatable shafts 17, 18, 19, and 20. These shafts 30, 31, and 32 are geared together by their respective gears 35, 36, and 37. The gear 35 on the shaft 30, besides meshing with the gear 36 on the shaft 31, also meshes with a gear 38 which is, like the gear 21, secured to the shaft 17. This shaft 17 is, as before stated, rotated through its gear 21 by the gear 15 on the shaft 10, the latter being driven through its gear 12 by the stationary gear 13 on the frame 2.

An idler shaft 40 is mounted on the side of the circular plate 5 which is opposite the frame 2 between the shafts 20 and 32. This idler shaft 40 carries a carding roll 41 which is provided with the usual card teeth.

Referring to Figure 2 of the drawings, it will be noted that the card teeth of the carding roll 26 are in contact with the card teeth of the carding rolls 25 and 41; also, that the card teeth of the carding roll 25 are in close proximity to the central aperture 6 in the circular plate 5; and that all of these carding rolls are substantially spaced from the circular plate. The circular plate 5 carries, on its side opposite the frame 2, a spool pin 45 on which there is carried a cone 46 of asbestos roving. The shaft 32, on which the gear 37 is mounted, also carries a rubber feed roll 47 which directs the asbestos roving from its spool pin 45 onto the card teeth of the carding roll 41 on the shaft 40. As the carding rolls 41, 26 and 25 are rotated, the asbestos roving is carded and delivered progressively onto the carding roll 25 which presents it to the central aperture 6 in the circular plate 5. The shapes and relative speeds of the carding rolls 41, 26, and 25 are

such that a loose entangled mass is delivered at the aperture for a purpose to be later described.

A relatively spaced cross-frame 53 is secured to the circular plate 5, on its side opposite the frame 2. This cross-frame 53 extends between the circular plate 5 and the adjacent sides of the carding roll 25 and is centrally apertured in alignment with the aperture 6 in the circular plate. Wire X is drawn, by suitable means, through the aperture 4 in the spindle 3, central aperture 6 in the circular plate 5, and the aligned aperture 54 in the spaced cross-frame 53, moving in the direction of the arrow of Figure 1.

The circular plate 5 carries, on its side opposite the frame 2, a rotatable shaft 55 to which there is secured a gear 56. The extended end of the rotatable shaft 55 extends through the cross-frame 53 and carries an eccentric 57 on the opposite side thereof. A rock-shaft 59 is intermittently journaled on the eccentric 57 in such manner as to present one of its ends in close proximity to the aperture 54 in the spaced cross-frame 53. This end of the rock-shaft 59 carries a series of picker teeth 60, the series being substantially equal in length to the width of the adjacent carding roll 25. The other end of the rock-shaft 59 is slotted, as at 62, to accommodate a pin 63 which is secured to the adjacent side of the spaced cross-frame 53.

30 A small electric motor 65 is secured to the circular plate 5, on its side opposite the frame 2, and carries a pinion 66. This pinion 66 meshes with an idler gear 68 which is carried by a shaft 69, the latter being likewise mounted on the circular plate. This idler gear 68 also meshes with the gear 56 on the shaft 55 which, as before stated, carries the eccentric 57.

On its side adjacent the frame 2, the circular plate 5 carries a pair of electrical collector rings 70 which receive current from a pair of fingers 71 that are carried by the frame 2. These fingers 71 receive current from any suitable source. The small electric motor 65 receives current from the collector rings 71 by means of wires 72.

45 Upon driving the small electric motor 65, the rock-shaft 59 is eccentrically rocked and moved toward and away from the carding roll 25, whereby its series of picker teeth 60 are forced into the card teeth of the latter and withdrawn with 50 a forward scooping motion which clears the asbestos fibers from this carding roll and deposits them on the wire X.

The spaced cross-frame 53 carries a longitudinally extending curved wiper 75 adjacent its aperture 54 for smoothing the asbestos fibers de-

posited by the series of picker teeth 60 on the rock-shaft 59.

Referring to Figures 1 and 6, it will be noted that, as the wire X carrying the deposited asbestos fibers moves from between the series of picker teeth 60 and curved wiper 75, it advances into a conventional forming head, generally indicated at 78, which serves to further compact the fibers. From the forming head 78 the wire X advances into a conventional ironing head 80 which further compacts and irons the asbestos fibers preparatory to the coating step. The forming head 78 and ironing head 80 may, if desired, be rotated in any suitable manner.

While I have shown and described one specific embodiment of my invention, it will be understood that I do not wish to be limited exactly thereto, since various modifications may be made without departing from the scope of my invention, as defined by the following claims.

I claim:

1. Apparatus for applying fibrous insulating material to an electrical conductor comprising a rotary head, said rotary head having an axial opening through which said electrical conductor passes, a spool of fibrous insulating material carried by said rotary head, carding means on said rotary head for applying said fibrous insulating material to said electrical conductor, means on said rotary head for assisting the removal of said fibrous insulating material from said carding means and onto said electrical conductor, driving means actuating said carding means during the rotation of said rotary head, and independent means for actuating said assisting means.

2. Apparatus for applying fibrous insulating material to an electrical conductor comprising a rotary head, said rotary head having an axial opening through which said electrical conductor passes, a spool of fibrous insulating material carried by said rotary head, carding means on said rotary head for applying said fibrous insulating material to said electrical conductor, means on said rotary head for assisting the removal of said fibrous insulating material from said carding means and onto said electrical conductor, driving means actuating said carding means during the rotation of said rotary head, independent means for actuating said assisting means, and means carried by and movable with said rotary head for smoothing the fibrous insulating material after its application to said electrical conductor.

OWEN A. MCNAMEE. 55
